CLAIM

The ornamental design for a wheeled support for a refuse sack, as shown and described.

DESCRIPTION

FIG. 1 is a front perspective view of a wheeled support for a refuse sack;

FIG. 2 is a rear perspective view thereof; and,

FIG. 3 is another front perspective view thereof.

The broken line showing of the wheels and bolts is included for the purpose of illustrating environment and forms no part of the claimed design.

1 Claim, 3 Drawing Sheets

FIG. 1

FIG. 2

FIG. 3
